Inventor
JOHN W. GURLEY,

James A. Walsh,

Attorney

UNITED STATES PATENT OFFICE

JOHN W. GURLEY, OF INDIANAPOLIS, INDIANA, ASSIGNOR OF ONE-HALF TO HAROLD TAYLOR, OF INDIANAPOLIS, INDIANA

FLUID-PRESSURE PUMP

Original application filed November 3, 1927, Serial No. 230,862. Divided and this application filed June 1, 1928. Serial No. 282,168.

My invention relates to improvements in fluid pressure pumps or motors for air and other fluids for different purposes of the character disclosed in my copending application serial No. 230,862, filed November 3, 1927, of which this is a division, and consists in improved means for constantly lubricating the actuating parts of such a pump, as will hereinafter more fully appear.

10 In the accompanying drawing, which forms a part hereof, Figure 1 is a vertical sectional view of a pump equipped with my improved lubricating system, and Fig. 2 is a detail, as seen when looking in the direction of the arrows 2-2 in Fig. 1.

In said drawing the numeral 5 indicates the crank-case, in which a balance-wheel 6 is mounted, and to which wheel and the piston 7 a connecting rod, as 8 is eccentrically secured, the balance-wheel being actuated by the shaft 9 to reciprocate the piston 7 (having a valve 7' thereon) in the cylinder, as 10, but as such pump is fully described in my application hereinbefore referred to it will only be necessary to refer to its general construction incidentally in describing my present improvement.

In an apparatus of the character referred to it is essential that its actuating parts be constantly and effectively lubricated, and for which purpose I combine therewith the oiling system constructed and arranged substantially as follows.

I provide an oil reservoir 12 to which the 35 crank-case 5 is secured, as by screw bolts 13, into which reservoir oil is supplied through an inlet 14. A passage 15 is provided through a wall of the reservoir and extends upwardly therein, and to which passage a 40 pipe 16 is connected, the vertical portion of the passage having a suitable valve therein for controlling the oil flow, and in practice I have found that a spring-controlled valve as 17 is satisfactory. The pipe 16 extends to 45 the upper end of cylinder 10 and is connected to its intake by a coupling 18 having an orifice 19 therethrough which preferably leads to a glass tube 20 in which the lubricant may be inspected, the tube in turn communicating 50 with an orifice 21 in the cylinder intake 10',

and in which orifice suitable material 22 is inserted for trapping dust particles and the like contained in the lubricant and thus filtering the latter. In the coupling 18 a needle-valve 24 is provided, the head 25 of which 55 may comprise a dial or indicator, Fig. 2, so that the valve may be set in a predetermined position by bringing a character on the dial in registry with a pointer 26 secured to the coupling 18 or otherwise.

As will be understood, the reciprocating action of the pistons and rotary action of the balance-wheel constantly draw oil from the reservoir 12 up through the pipe 16 and the orifice communicating therewith, and by 60 means of the needle-valve 24 such lubricant is caused to pass into the intake 10' in atomized condition, so that during the operation of the apparatus the lubricant is continuously spraying into the intake and thence finds 65 its way through valves 7 and 7' into the spaces between the casing 5 and wheel 6, and also into the piston-rod connections and into cylinder 10 to lubricate all of the interior parts, while any undue surplus carried 70 between the lower side of said wheel and casing is forced through the opening 30 in the upper side of the reservoir 12, which opening is normally closed by a spring-controlled 75 valve 31 until the pressure of the oil displaces it, when the oil flows into the reservoir to be reused, the valve becoming automatically closed whenever such pressure is relieved. In the manner described it will therefore be 80 apparent that during the operation of the pumping apparatus a continuous supply of lubricating material is circulated from the oil reservoir up into the cylinder and returned, thus assuring that the supply will 85 be constant at all times and the actuating 90 parts of the apparatus thoroughly lubricated.

I claim as my invention:

1. In an apparatus of the character described, in combination, an oil reservoir, a crank-case associated with the reservoir, a shaft extending into the crank-case, a wheel on the shaft, a connecting-rod mounted on the wheel, a piston connected to the rod, a cylinder in which the rod and piston reciprocate, means exteriorly of the crank-case connected 100

5 to the reservoir and with the cylinder for conveying oil therefrom and discharging the same into the cylinder during the reciprocation of the piston, and means for returning surplus oil from the crank-case into the reservoir.

10 2. In an apparatus of the character described, in combination, an oil reservoir, a crank-case associated with the reservoir, a shaft extending into the crank-case, a wheel on the shaft, a connecting-rod mounted on the wheel, a piston connected to the rod and having a valve associated therewith, a cylinder in which the rod and piston reciprocate said cylinder having a valve associated therewith, means for enclosing the wheel and parts associated therewith in the crank-case, means for conveying oil from the reservoir into the cylinder, and means for atomizing the oil as 15 it discharges into the cylinder.

20 3. In an apparatus of the class described, in combination, an oil reservoir, a crank-case associated with the reservoir, a shaft extending into the crank-case, a balance-wheel on the shaft, a connecting-rod mounted on the wheel, a piston connected to the rod, a cylinder in which the rod and piston reciprocate, a pipe connected at one end to the reservoir, a coupling connecting the opposite end of the 25 pipe to the cylinder, and means for actuating the piston to propel oil from the reservoir to the cylinder to lubricate the latter and parts associated therewith.

30 4. The combination, with an apparatus of the class described, of an oil reservoir embodying a passageway leading therefrom, a conduit communicating with said passageway, a valve in the passageway, a coupling connecting said conduit to the apparatus, a transparent element secured to the coupling through which lubricant may be inspected, a needle-valve in the coupling for controlling the discharge of lubricant through the latter, means for actuating the apparatus to circulate 35 a lubricant from said reservoir through the apparatus, and an indicating device associated with said coupling for determining the amount of lubricant passing therethrough.

40 In testimony whereof I affix my signature.
JOHN W. GURLEY.
